UNITED STATES PATENT OFFICE.

WILLIAM E. GILKEY, OF BOW, WASHINGTON.

GATE.

1,247,817.

Specification of Letters Patent.

Patented Nov. 27, 1917.

Application filed April 18, 1917. Serial No. 163,021.

To all whom it may concern:

Be it known that I, WILLIAM E. GILKEY, a citizen of the United States, residing at Bow, in the county of Skagit and State of Washington, have invented certain new and useful Improvements in Gates, of which the following is a specification.

This invention relates to gates and more particularly to an improved gate for providing an obstruction to gateways whereby cattle will be prevented from passing through the gateway, while the construction of the gate will permit automobiles and similar vehicles to pass through the gateway without the necessity of stopping the vehicle to open the gate.

One of the objects of the invention is to provide a pair of complementary gate members co-acting to close the gateway when in operative position and arranged to automatically open and close when an automobile passes through the gateway.

A further object of this invention is the provision of a gate which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which;

Figure 1 is a longitudinal vertical section through the gate constructed in accordance with my invention.

Fig. 2 is a vertical transverse section.

Referring to the drawing, wherein is illustrated the preferred form of my invention, and in which like numerals of reference indicate corresponding parts throughout the several views, the gate posts 1 and 2 are spaced apart the required distance to form the desired width of gateway and these gate posts support the fence boards 3 in the usual manner.

Between the gate posts, I have provided a frame which is sunk partially into the ground and the same consists of the side stringers 4 and 5 and a central stringer 6. The ends of these stringers are fastened to the end cross-pieces 7, the latter being sunk into the ground and attached to the lower edges of the supports as clearly shown by

Fig. 1. Each terminal of each stringer has its upper edge cut away at an angle thus providing the beveled ends 8 and 9 for each stringer. Fixed to these beveled ends at each end of the frame, is an angularly disposed tread piece 10. Permanently fixed to the upper edges of the stringers is a plurality of longitudinally spaced tread boards 11, the same having their edges beveled so that the bottom of each tread board is wider than the top. This construction provides a plurality of wedged shape spaces between the tread boards the purpose of which will be presently described.

The angular tread pieces 10 carry the hinges 12, while fixed to the hinges is a pair of complementary gate members 13 and 14. Each gate member consists of the side beams 15 to which is connected the ends of a plurality of slats 16, the longitudinal edges of which are cut at an angle opposite to the beveled edges of the tread boards 11 and the width of the slats is substantially equal to the space between the tread boards as clearly shown by Fig. 1 of the drawing. The outer ends of the beams 15 are attached to the leaves of the hinges 12 so that the complementary gate members are free to swing upwardly to the positions shown by dotted lines in Fig. 1. When swung downwardly, the slats 16 fit in the space between the tread boards 11, thus providing a comparatively smooth surface over which the automobile may pass when driving through the gateway. One of the side beams 15 of the gate member 14 carries an arm 17 which extends beyond the end of the beam and overlaps the proximate end of the adjacent beam on the gate member 13 when the two gate members are closed. The other gate member 13 has the beam 15 on the opposite side provided with a similar arm 18 which projects in the opposite direction from the adjacent beam of the gate member 14. These arms are extended as shown by dotted lines in Fig. 1 for the purpose of forcing both the gate members downwardly when an automobile passes over the gate members and thus assures positive action on the gate members in the event the hinges become stiffened and tend to stick when the automobile contacts with the complementary gate member.

The top of each gate post is bifurcated and mounted in each bifurcation is a pulley 19 over which is passed a cable 20. The in-

ner end of each cable is fixed to the loop 21, the terminals of which are fixed to the proximate ends of the complementary gate members at each side thereof. The opposite end 5 of each cable 20 carries a weight 22 acting to maintain the complementary gate members in raised position for closing the gateway so that cattle will be prevented from passing through the gateway.

- 10 It will be obvious that it is merely necessary to drive the vehicle over the edge of the tread piece 10, according to the side of the gate approached by the vehicle. When the front wheels contact with the gate members, the same will be forced downwardly and the weights will be lifted, while the gate of the other gate member will cause it to also drop, so that when the vehicle reaches the center of the gateway both gate members will be in a position to permit the vehicle to pass through the gateway. The arms 17 and 18 will cause positive action on either gate member in the event the same should not drop from their own weight when 25 the other gate member is forced downwardly by the vehicle.

For permanently fixing the gate in open position, so that cattle may be permitted to pass through the gateway when desired, I 30 have provided a pin 23 driven into the center of the central support 6 at the exact center of the gateway. The pin projects above the stringer and carries a rotatable latch 24 which may be engaged with the outer surface 35 of the proximate slats at the end of each gate member for the purpose of holding the gate members in open position against the tendency of the weights to hold them in closed position. As soon as the cattle have passed through the gate, it is merely 40 necessary to give the latch a quarter turn and the weights will force the gate members to closed position.

From the foregoing it will be observed 45 that a very simple and durable gate has been provided, the details of which embody the preferred form. I desire it to be understood however, that slight changes in the minor details of construction may be made without departing from the spirit of the invention or the scope of the claims hereunto appended.

Copies of this patent may be obtained for five cents each, by addressing the "Commissioner of Patents, Washington, D. C."

I claim:

1. The combination with a pair of gate posts and a frame arranged between the gate 55 posts, of a plurality of tread boards mounted on the frame, and a pair of complementary gate members hingedly mounted at either end of the frame and provided with slats received in the space between the tread 60 boards when the gate members are in open position.

2. The combination with a pair of gate posts spaced to provide a gateway, a frame 65 mounted in the gateway and embedded partially below the ground surface, a plurality of tread boards carried by the frame, and a pair of complementary gate members hingedly mounted on the frame to normally dispose and close the gateway, the said gate 70 members including slats received between the tread boards when the gate members are forced into contact with the frame.

3. The combination with a pair of gate posts spaced apart to provide a gateway, 75 a pair of complementary gate members hingedly mounted and normally co-acting to close the gateway, the said gateway including a plurality of slats, supporting means for the gate members, and a plurality of 80 tread boards longitudinally spaced and adapted to receive therebetween the said slats when the complementary gate members are in open position.

4. The combination with a pair of gate 85 posts spaced apart to provide a gateway, a pair of complementary gate members hingedly mounted and normally co-acting to close the gateway, the said gateway including a plurality of slats, supporting means 90 for the gate members, a plurality of tread boards longitudinally spaced and adapted to receive therebetween the said slats when the complementary gate members are in open position, and gravity operated means 95 for maintaining the gate members in raised positions.

In testimony whereof I affix my signature in presence of two witnesses.

WILLIAM E. GILKEY.
